UNITED STATES PATENT OFFICE.

KARL WIESER, OF BREDENEY, GERMANY, ASSIGNOR TO FRIED. KRUPP AKTIEN-GESELLSCHAFT, OF ESSEN-ON-THE-RUHR, GERMANY.

IMPACT-FUSE.

No. 911,792.

Specification of Letters Patent.

Patented Feb. 9, 1909.

Application filed August 28, 1907. Serial No. 390,482.

To all whom it may concern:

Be it known that I, KARL WIESER, a subject of the Emperor of Germany, and a resident of Bredeney, Prussia, Germany, have 5 invented certain new and useful Improvements in Impact-Fuses, of which the following is a specification.

The present invention relates to impact fuses having a delay action means capable 10 of being shifted to and from effective position and the object of the invention is to do away with the so-called delay-charges. These powder charges have the drawback that they become destroyed by the pressure 15 caused by the explosion of the primer and, therefore, burn instantaneously, that is to say, they do not cause any delay of the ignition, and this is in particular the case when the charges are made small for the purpose 20 of obtaining a short delay.

The accompanying drawings show two embodiments of the invention applied to a base fuse, by the way of example.

Figure 1 is an axial longitudinal section 25 through one embodiment; Fig. 2 is a bottom view of the same; Fig. 3 is a section on line 3—3, Fig. 1, looking from above; Fig. 4 shows a part of the second embodiment in a view corresponding to that shown in Fig. 30 1, and Fig. 5 is a section on line 5—5, Fig. 4, looking from above.

Reference will first be had to the embodiment shown in Figs. 1 to 3. The bolt B carrying the primer A, the safety spring C 35 and the firing pin D are arranged in a bushing E which is rotatably but non-slidably mounted in the fuse housing F. The bushing E can be adjusted by means of a screw plug G which closes the bushing towards the 40 exterior and which has its head provided with a slot g' for the engagement of a suitable key. The inner end of the bushing is provided with a bore e' which is eccentric to the axis of rotation of the bushing and in 45 which is located a powder charge H adapted to increase the igniting flame. Above the bushing E an insertion-piece K is arranged in the housing F and is held against rotation. The insertion piece K is provided 50 with two separate channels L M which serve to conduct the igniting flame of the primer to a powder charge P which is adapted to ignite a detonator (not shown) arranged between the bursting charge of the 55 projectile and the fuse. The mouths of the

channels L M adjacent to the bushing E are the same distance from the axis of rotation of the bushing E as the bore e'. The bore e' can, therefore, by turning the bushing E, be adjusted in such a manner that either the 60 channel L or the channel M serves as connection between the powder charge P and the ignition chamber of the impact fuse. The channel M is considerably longer than the channel L; it leads at an inclination upwardly from the bushing E, extends then to the outer surface of the fuse, (see Fig. 3) in a plane at right angles to the longitudinal axis of the fuse, thence in the same plane to its end portion which is also inclined upwardly and terminates opposite to the powder charge P. The igniting flame therefore, consumes longer time in traversing the path formed by the channel M than in passing through the channel L. This difference in 75 time is partly caused by the fact that the fire-jet in traversing the channel M is obliged to change its direction at three places by reason of the above-described shape of the channel M. In the channel M are preferably arranged small perforated powder-bodies m' m'' of such a nature that they can burn or explode instantaneously. These powder-bodies are merely for the purpose of increasing the igniting flame from the 80 primer or kindle the fire-jet afresh. The remaining part of the channel M is empty as is also the channel L. Between the insertion-piece K and the upper end of the bushing E is located a packing disk N of cloth or the 85 like which is secured on the bushing E and has a perforation n' registering with the bore e'.

In the drawing, the bushing E is in the position in which its bore e' communicates 95 with the short channel L. When, on the impact of the projectile, the firing pin D hits the primer A, the igniting flame will consequently pass without delay to the powder charge P through the bore e' and the channel L, and the projectile will therefore burst at the moment of impact. If, however, the ignition is to take place with delay, the bushing is, by means of the screw-plug G, turned to that position in which the bore e' registers with the channel M. With this adjustment of the fuse, a certain time elapses between the moment of impact and the ignition of the powder charge P. The correct adjustment of the bushing is indicated by 105 110

the marks Q R S which are arranged on the head of the screw-plug G and on the bottom of the fuse housing F.

It is evident that several channels of different length could be provided in the insertion-piece K for the purpose of obtaining delays of different duration.

If the primer is of sufficient force or the powder charge P is sufficiently sensitive the strengthening charges m' m^2 may be done away with.

In the embodiment shown in Figs. 4 and 5 a channel T is cut in that wall of the insertion-piece K that is towards the bushing E. The channel T extends in a broken line, and has arranged therein a strengthening charge t' . The channel is not endless; both its ends t^2 t^3 and a point t^4 intermediate of the ends have the same distance from the axis of rotation of the bushing E as the bore e' . The end t^2 of the channel T communicates with the powder charge P through the medium of a bore V in the insertion-piece K. When the bore e' of the bushing E registers with the end t^2 of the channel T the igniting flame of the primer passes without delay through the bore V to the powder charge. When the bore e' is adjusted to the joint t^4 or to the end t^3 of the channel T delays of different duration take place in the ignition.

Having thus described the invention, what is claimed and desired to secure by Letters Patent is:

1. An impact fuse having an open channel for the igniting flame, said channel being circuitous in its course whereby it causes the igniting flame to change its direction and effects delay in the transmission of the igniting flame without the interposition of retarding combustible material.

2. An impact fuse having an open chan-

nel for the igniting flame, said channel being circuitous in its course whereby it causes the igniting flame to change its direction and effects delay in the transmission of the igniting flame without the interposition of retarding combustible material, said channel being provided with perforated powder charges, which while permitting immediate transmission of the igniting flame are ignited by and reinforce the same.

3. An impact fuse having a direct action open channel and an open channel for the igniting flame, said last named channel being circuitous in its course whereby it causes the igniting flame to change its direction and effects delay in the transmission of the igniting flame without the interposition of retarding combustible material, and means for introducing either of said channels in the conducting position at will.

4. An impact fuse having a direct action open channel and an open channel for the igniting flame, said last named channel being circuitous in its course whereby it causes the igniting flame to change its direction and effects delay in the transmission of the igniting flame without the interposition of retarding combustible material, said circuitous channel being provided with perforated powder charges which while permitting immediate transmission of the igniting flame are ignited by and reinforce the same, and means for introducing either of said channels in the conducting position at will.

The foregoing specification signed at Dusseldorf, Germany, this 12th day of August, 1907.

KARL WIESER.
